HAT MACHINE

Frank Forrest Dow, Jamaica, N. Y., assignor to
 M. A. Cuming & Company, Inc., New York,
 N. Y., a corporation of New York

Application May 25, 1940, Serial No. 337,137

6 Claims. (Cl. 223—13)

This invention relates to a hat forming machine and more particularly to a machine of the general type disclosed in Patent No. 2,064,824, wherein a top block or head is fixedly mounted in the upper portion of the machine and an elevator is raised or lowered with respect to the head or top block and has mounted thereon a carriage on which the bottom block is mounted. The invention also relates to hat forming machines of the type shown in Patent No. 1,526,000, in which differential pressure is applied to those portions of the structure shaping the crown and brim of the hat, respectively.

Heretofore in hat forming machines of the character described while the elevator has been actuated manually, it has also been necessary to move the carriage manually to a position at which the hat blank may be inserted and removed from the female block, this resulting in considerable loss in time and confusion in manipulation.

The primary object of the present invention is a hat forming machine in which, when a felt blank has been placed in the one block and relative movement of the two blocks commenced, the carriage is automatically moved into position to register with the other block, and when the blocks are separated, the carriage is at the same time moved outwardly automatically to permit removal of the hat.

Another object of the invention is a hat forming machine in which the speed of movement of the carriage on the support changes in accordance with the relative position of the support relative to the head in the interest of speed of operation.

It has heretofore been proposed to alternately inflate and deflate the rubber die placed over a felt blank in the manufacture of hats in an effort to obtain a more even felting of the hat and avoid excessive thickness. The present invention also seeks an improvement over such prior proposals by applying pulsating pressures to the two areas at which different pressures are applied thereby causing a more effective felting of the fibers.

The invention also seeks a hat machine which is practical from the standpoint of ease and simplicity of manufacture and rapidity and convenience of operation.

These and other objects of the invention and the means for their attainment will be more apparent from the following detailed description, taken in connection with the accompanying drawings illustrating one embodiment by which the invention may be realized and in which:

Figure 1 is a view in side elevation showing the hat machine of this invention with the hat blocks in closed position;

Figure 2 is a view similar to Figure 1 but with the blocks in fully opened position;

Figure 3 is a fragmentary view on an enlarged scale showing the means for automatically actuating the carriage, parts being sectioned to illustrate details of construction;

10 Figure 4 is a view in transverse section taken in the plane indicated by the line 4—4 of Figure 2 and looking in the direction of the arrows and showing the carriage in plan; and

Figure 5 is a sectional view, on an enlarged scale, showing the hollow head block and the means for applying pulsating pressure to the crown of the die.

The hat forming machine of this invention comprises generally two upright frame members 20 serving as guides or ways for an elevator or support 13. These frame members 1 are rigidly mounted upon a base indicated generally by the reference character 9 and are held at their respective upper portions by a so-called fixed head 11 supporting the upper block of the combination. Reciprocal on the ways 7 is an elevator 13 having bearings 15 sliding on the ways 7 and consisting of a generally rectangular frame as viewed in Figure 4 having a substantially horizontal upper surface and counterweighted as by the weight 17 connected as by cables 19 to the elevator 13 and turning over a cam-shaped wheel 21 rotatably mounted on a transverse shaft 23 carried on the top block.

35 In the lower part of this frame is a transverse rock shaft 25 having an operating handle 27 and having, on each side, inwardly of the uprights 7, an arm 28 fixed thereto and connected to the elevator by a link 29 whereby, when

40 the shaft 25 is rocked, as by the handle 27 between the position shown in Figure 2 and the position shown in dotted lines in Figure 1, the elevator 13 is raised or lowered, as the case may be, as will be readily understood. When the

45 carriage is in its elevated position, and to prevent the carriage being moved downwardly when the handle 27 is moved through more than 180° to a position on the opposite side of the uprights 7 from that illustrated in Figure 2, an arm 30 carried by the link 29 engages the shaft as a stop, as shown in Figure 1.

On the elevator is a pair of rails 33 formed with a depression 35 at their inner ends in which a pair of wheels of a carriage may rest and the rails are provided at their inner ends with

pins 39 to form a stop for the carriage next to be described.

The carriage constitutes the bottom block 41 and has four depending legs 43 on which wheels 44 are mounted to run on the tracks 33 between the position shown in Figure 1 where the rear wheels are in the depressions 35. The ends 37 of the arms 43 serve to prevent the wheels leaving the track.

Movement of the carriage 41 is effected by an arm 45 fixed on the shaft 29 and rotatable about the axis thereof upon movement of the handle 27. In its inoperative position the arm 45 takes the position illustrated in Figure 1 directed to the rear of the machine. At its end, the arm 45 is provided with a transversely extending pin or lug 47. Preferably axially aligned pins extend outwardly on either side of the arm 45. Then, as the handle 27 is rotated from the position shown in Figure 1, to the position shown in Figure 2, the arm 45 swings through an arc indicated by the broken line in Figure 2.

On the rear end of the carriage is mounted a bracket 59 having guide means illustrated as vertically disposed spaced parallel walls 52 in the opposed faces of which are formed registering cam grooves 54 one of which is shown in detail in Figure 3. These cam grooves are open at their bottom ends as at 56 and extend forwardly and upwardly at an angle to the vertical as at 58 to the most advanced point 60. From point 60 the cam grooves extend upwardly and rearwardly at an angle to the vertical as at 62 and terminate in upwardly extending groove portions 64 which are closed at their upper ends.

The operation of the arm and the movement of the carriage will be best understood from the following description of the operation of the hat forming machine of this invention. Assuming that the machine is open as shown in Figure 2 with the carriage in its lowermost position and at the front end of the elevator where access can be readily had to the block thereon, a felt bat is placed in the lower block in a desired manner and the handle 27 swung to the position shown in Figure 1 and the elevator and carriage elevated to a position in register with the head where the necessary forming and pressing operations are performed. After such operations are completed, the handle is swung down to the position shown in Figure 2. This cause the elevator 13 to move downwardly and, in so moving, carrying with it the carriage 41. As the carriage moves downwardly, the arm 45 swings preferably coincidentally with the elevator in a counter-clockwise direction, as viewed in Figure 2, until the pin 47 on the end of the arm 45 reaches the mouth 56 of the cam groove. Then as the elevator 13 continues its downward movement and the arm 45 continues in its counter-clockwise movement, the movement of the pin 47 in that portion 58 of the cam groove causes the carriage 41 to move to the left, as viewed, on the track 33, at the same time that the carriage is being carried downwardly by the elevator 13. It will be noted that the cam groove changes its direction, see Figure 3, at the portion marked 60, and changes its direction to a generally upwardly and rearwardly direction so that as the arm 45 continues its counter-clockwise direction so that as the pin 47 on the arm 45 travels in the inclined portion 62 of the cam groove, the carriage is given an increased speed of movement to the left as viewed in Figure 2 and more rapidly reaches the extreme position

while, at the same time, the elevator travels downwardly to its lowermost position over a shorter distance. Then at the end of the travel of the elevator which coincides with the movement of the arm 45 in its extreme left hand position as illustrated in Figure 2, the pin 47 enters the vertically extending groove 64 and remains stationary to lock the carriage in its outermost position. Similarly, when a bat of felt is placed in the mould on the carriage at the beginning of a forming operation, and the arm 27 thrown in a clockwise direction the pin 47, being in the groove position 64, commences to move the carriage quite rapidly to the right as viewed in Figure 2. At the same time after a predetermined movement of the handle 27, the elevator 13 commences to rise and the pin 47 is therefore positioned further and further down in the groove portion 62 until by reason of the upward movement of the carriage it enters the groove portion 58 and moves the carriage more slowly until finally the carriage reaches a position in register with the hollow head 11 where the lugs 47 leave the groove, and the female die with the felt bat therein continues its upward movement to be brought into cooperating engagement with the die 76-88 in the head 11.

As illustrated in Figure 5, the upper wall 70 of the hollow head 11 is formed centrally with a depending portion 72 formed with a vertical passage 74. A brim forming disc like element 76 of flexible material such as rubber is carried on the lower edge 78 of the head and is of such size and shape as to extend upwardly and be in contact with a spacing and positioning plate 80 interposed between the depending portion 72 and the brim forming element 76, an aperture 82 in the brim forming element 76 and an aperture 84 in the plate 80 registering with the passage 74. Sealing means 79 may be disposed between portion 72 and the plate 80. The dome or crown forming bag element 86 which is also of yielding material, such as rubber, may take any form and has formed integral therewith an inwardly extending lip or flange portion 88 which is held in place by disc 90 having an aperture 91 registering with the passage 74 so that the element 86 is substantially a closed body with only the aperture 91 in register with the passage 74. The inner surface of this top wall 88 is provided with an annular depending rib 92 which is received in the annular groove 94 in the plate 90 adapted to retain the parts in proper positions. Plate 90 is held in position by bolts 96 shown as diametrically disposed upon opposite sides of the passage 74 and passing through registering holes in the parts 72, 80, 76, 88, and 90 and accessible from without the head 70.

Fluid either liquid or gaseous enters the space between the brim forming element 76 and the dome 70 from one source (pipe 97) and enters the male member 86 through the pipe 99 entering cylinder 98 registering with passage 74.

In order that this forming operation on the crown of the hat may include a certain ironing effect to cause the fibers of the felt to knit together more firmly, it is proposed to place a pulsating pressure on the fluid within the crown portion 86. Of course, the pulsating pressure may also be applied to the brim portion. To this end, the pipe 98 serves as a cylinder in which reciprocates a piston 100 actuated by a pitman 102 driven in any convenient fashion as by the motor 104 to which it is connected by suitable means shown as the eccentric cam 106. The pis-

ton 100 is caused to reciprocate within the cylinder 98 to apply a pulsating pressure to the fluid within the element 86 and the consequent vibration of the yielding non-metallic flexible material forming the male member 86 causes an effective smoothing of the fibers of the felt forming the crown of the hat.

It will thus be seen that a hat forming machine has been provided which contributes to the rapid formation of a hat. Thus, a felt bat is placed in the mould on the carriage when the elevator is in its lowermost position and by a single movement of the lever 27 the hat is moved into cooperative relation with the die member on the dome or hollow head. During the ironing or forming operation, if desired, a kneading effect of the fibers of the bat may be effected by the motor driven pulsator and after the hat forming operation is completed, a throw of the lever in the opposite direction causes the separation of the dies and the movement of the female die to an accessible position at the outer end of the elevator without additional manual manipulation. This results in a considerable saving of time.

Various modifications will occur to those skilled in the art in the composition, configuration and disposition of the component elements going to make up the invention as a whole as well as in the selection and combination or relative movement of particular features to accomplish specific results, and no limitation is intended by the phraseology of the foregoing description or illustrations in the accompanying drawings except as indicated in the appended claims.

What is claimed is:

1. In a hat machine, the combination with a frame and a fixed head carried therewith, of an elevator reciprocable with respect to the head, a bottom block movable on the elevator between a position in register with the head and a position permitting the insertion and removal of a hat from the bottom block and guide means carried by the carriage and an arm movable coincidentally with the elevator to coact with the guide means to move the bottom block with respect to the elevator.

2. In a hat machine, the combination with a frame and a fixed head carried therewith, of an elevator reciprocable with respect to the head, a bottom block movable on the elevator between a position in register with the head and a position permitting the insertion and removal of a hat from the bottom block and cam groove means carried by the carriage, an arm movable synchronously with the elevator and a pin on the arm adapted to be received in the cam groove to move the bottom block with respect to the elevator.

3. In a hat machine, the combination with a frame and a fixed head carried therewith, of an

elevator reciprocable with respect to the head, a bottom block movable on the elevator between a position in register with the head and a position permitting the insertion and removal of a hat from the bottom block and spaced plates, opposed faces of which are formed with cam grooves and carried by the carriage, an arm movable synchronously with the elevator and pins on the arm adapted to be received in the cam

5 grooves to move the bottom block with respect to the elevator.

4. In a hat machine, the combination with a frame and a fixed head carried therewith, of an elevator reciprocable with respect to the head, a bottom block movable on the elevator between a position in register with the head and a position permitting the insertion and removal of a hat from the bottom block and a cam groove extending upwardly at different angles to the vertical and carried by the carriage, an arm movable synchronously with the elevator and a pin on the arm adapted to be received in the cam groove to move the bottom block with respect to the elevator.

5. In a hat machine, the combination with spaced vertical frame members, a fixed head carried at the top of the members, an elevator slideable on the frame members, a shaft, a pitman between the shaft and the elevator whereby the elevator is moved toward and away from the fixed head upon rotation of the shaft, a carriage movable on the elevator and adapted to support a bottom block, said carriage having a track, an arm fixed on the shaft and a pin on the end of

35 the arm movable in the track to actuate the carriage.

6. In a hat machine, in combination, a head member having a depending central portion formed with a passage and bolt holes on opposite 40 sides of the passage, a disc like brim forming element of yielding non-metallic material formed with an aperture to register with the passage in the head and bolt holes to register with the holes in the head, means to secure the periphery 45 of the brim forming element to the head, a plate between the brim forming element and the head and formed with an aperture to register with the passage in the head and bolt holes to register with the bolt holes in the head, sealing means between the plate and the depending portion of 50 the head, a crown bag formed with an inwardly directed lip, said lip being formed with a continuous bead on its surface, a retaining plate within the crown bag formed with a continuous 55 groove in its upper surface to receive the bead on the crown bag and threaded apertures to register with the aforesaid bolt holes and an aperture therebetween to register with the passage and bolts in the bolt holes.

FRANK FORREST DOW.
